US00D864284S

(12) **United States Design Patent** (10) **Patent No.:** **US D864,284 S**
(45) **Date of Patent:** **** Oct. 22, 2019**

(54) **DIGITAL WELDING GOGGLE**

- (71) Applicant: **Ningbo Geostar Photoelectric Technology Co., Ltd.**, Ningbo, Zhejiang (CN)
(72) Inventors: **Zhaolin Yang**, Zhejiang (CN); **Jianrong Zhou**, Zhejiang (CN); **Rongjiang Wang**, Zhejiang (CN)
(73) Assignee: **Ningbo Geostar Photoelectric Technology Co., Ltd.**, Ningbo (CN)

(**) Term: **15 Years**

(21) Appl. No.: **29/650,988**

(22) Filed: **Jun. 12, 2018**

(30) **Foreign Application Priority Data**

- Apr. 13, 2018 (CN) 2018 3 0150930
(51) LOC (12) Cl. **16-06**
(52) U.S. Cl.

CLAIM

The ornamental design for a digital welding goggle, as shown and described.

DESCRIPTION

FIG. 1 is a front elevational view of a digital welding goggle showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, rear and right side perspective view thereof;

FIG. 9 is a bottom, front and right side perspective view thereof; and,

FIG. 10 is a bottom, front and left side perspective view thereof.

The oblique shade lines in the drawings represent reflective surfaces.

1 Claim, 10 Drawing Sheets
